SUPPORT FIXTURE

Elton H. Tubbs, Westfield, N. Y., assignor to General Electric Company, a corporation of New York

Application May 17, 1957, Serial No. 659,801

2 Claims. (Cl. 310—240)

My invention relates to a support fixture and, more particularly, to a support fixture for maintaining the tips of brush pressure springs of a dynamoelectric machine in a raised position to facilitate removal of the brushes.

For many years the electrical industry maintenance people have attempted to retract brush pressure springs with screwdrivers and other unsuitable instruments. Generally, such operation requires the use of two hands, one to hold the lever tip in a retracted position and the other to manipulate the brush. With larger machines such as those having 600 volt, 1,000 horsepower ratings, this is both hazardous and difficult. With a locomotive traction motor which is supported on the unsprung axle and subjected to severe vibrations, the spring tension must be sufficient to maintain the brushes in electrical contact with the commutator despite inherent mechanical shocks.

Experience has led to the use of insulation between the spring lever tip and the brush to prevent current flow within the spring thus preventing temperature rise thereof above the ambient to eliminate tempering of the steel of the spring. With the tension required, one of the most common hazards is the recurring damage caused by the use of improvised holding instruments such as sharp steel screwdrivers directly on relatively soft insulation secured to the spring lever tip. Another hazard is the probability that the spring lever tip will slip from its retracted position and because of its momentum will damage the brush itself or any intervening material such as the insulation or the operator's fingers. The hazard is further increased by the fact that certain of the brushes are placed in a relatively inaccessible position whereby the operator is able to use only one hand at a time to change a brush.

Therefore, an object of my invention is to provide a simple and reliable support fixture adapted to maintain prestressed springs in a retracted position.

In carrying out my invention in one preferred form, I have provided a support fixture adapted to be securely positioned on the brush holder and provided with rungs suitable to maintain the spring lever tips in the retracted position.

The subject matter which I regard as my invention is particularly pointed out and distinctly claimed in the concluding portion of this specification. My invention, however, as to its organization and method of operation together with further objects and advantages thereof will best be understood by reference to the following description taken in connection with the accompanying drawing, in which:

Fig. 1 shows a top plan view of a brush holder having my invention secured thereto;

Fig. 2 shows a side view of the arrangement shown in Fig. 1; and

Fig. 3 is an enlarged perspective view of my support fixture.

Referring now to the drawing, in which like numerals refer to similar parts, in Fig. 1, I have shown a brush

2

holder 10 adapted to support a plurality of brushes 11 which engage a commutator 12. The brush holder 10 may be fabricated, cast or molded of a rigid material which will support the brushes 11 in the apertures 13 substantially perpendicular to the adjacent surface of commutator segments. The apertures 13 are positioned at a precise electrical point on the commutator 12 located a fixed distance from the support pins 14 which are secured to a stationary frame (not shown).

10 With a relatively large machine, it is the usual practice to provide spiral brush springs 16 non-rotatably secured to the brush holder 10 with the end portion or spring lever tips 18 extending outwardly to engage the top of a brush 11 to maintain adequate brush contact on the

15 commutator 12. In order to provide desirable tension at the commutator surface, the normal pressure and line of motion of the tips 18 is parallel to the major axis of the brushes 16.

To prevent chattering or vibration of the brushes 11 despite violent vibrations of the dynamoelectric machine itself, it is essential that the pressure provided by springs 16 be on the order of several pounds. Also, since the tip 18 must be relatively rigid, it is made with a relatively large mass. This alone would cause a sufficient momentum, should the spring lever tip 18 be raised and then released to drop on the top of the brush, to damage the brush and, of course, any soft material between the top of the brush 11 and the tip 18.

20 It has been found that a current flow in the spring 16 will tend to heat the springs, temper them and destroy the desired resilience. Usually there is a relatively soft insulation material 20 secured between the tip 18 and the brush 11 to prevent an electrical connection therebetween. The material 20 is some type of non-conductive plastic or rubber which effectively prevents any current flow within the brush springs 16.

25 Also, if a maintenance man happened to have a knuckle or a finger in the region of the top of the brush 11, unexpected release of the brush tip 18, of course, would bruise it.

According to my invention, the brush lever tip 18, when raised from its operating position, is placed on a rung 22 of my support fixture 23. The rung 22 projects outwardly perpendicular to the line of motion of the tip 18 a distance sufficient to provide suitable support. In order to prevent slipping of the lever tips 18, I prefer to have the supporting surface of the rung 22 roughened or knurled as shown on Fig. 3. Moreover, I have provided enough space between the rung 22 and any adjacent structure to allow raising or lowering of the tips 18 without interference. As shown more clearly in Fig. 3, the rungs 22 are secured by a weld or braze to curved support members 24 which are mounted on the brush holder 10. The support members 24 are specifically designed to maintain the rungs 22 a sufficient distance above the brush holder 10 to support the tip 18 in a position which will not interfere with removal of the brushes 11. In order to prevent slipping of the brush support members 24, they are provided with recesses 25 between bifurcations which straddle the partitions 26 (Fig. 1) of a brush holder 10. A chamfer is provided on the bifurcations to facilitate assembly in the brush holder 10. This is especially helpful when the brush holder can not be seen. On the back of the members 24 I have provided a step 27 which also rests on the partitions 26.

60 In the particular brush holder illustrated in Figs. 1 and 2, the springs 16 are supported on a transverse rod 28. I have found that it is preferable to provide a support fixture 23 that will not tilt when it is engaged by only one of the tips 18 at either end. In order to prevent such tilting, I have provided the curved support members 24 with a

latching means shown as the extensions 30 which pass under and engage the under side of the rod 28.

In addition, I have connected the two curved support members 24 by a rigid brace or cross member 32, which is securely fastened to each by welding or brazing to provide a rigid one piece fixture. The cross member 32 is located behind the tip 18, when in the retracted position, so that it will not interfere therewith.

It is readily apparent from Fig. 2 that my support fixture may be easily positioned for use by placing the extensions 30 under the rod 28 and the lowering the curved portions 24 until the recesses 25 engage the partitions 26. I prefer to have the fixture 23 securely fastened when a single lever spring tip is placed on any one of the rungs 22 (as shown at 18a). In this manner, it will remain in place as long as the operator wishes to work on the brush holder 10 assembly regardless of the location within the machine of the particular brush holder. In other words, the brush holder 10 may be located on either side, above or below the commutator 12.

It should also be noted from Fig. 2 that I have shown a worn brush 11a, and a replacement brush 11b. In Fig. 1, I have shown aperture 13a where the brush has been removed prior to replacement. According to my invention, one or all three of the brush lever spring tips 18 could be mounted on the rungs 22 at the same time whereby one or all three of the brushes could be removed in one operation by the maintenance man reaching into the machine with one hand.

While I have illustrated and described particular embodiments of my invention, other modifications will occur to those skilled in the art. For instance, I contemplate that a fixture including the rungs 22 may be fabricated as shown or molded as a part of a modified brush holder. Obviously, my fixture is adaptable for supporting any number of spring lever tips by providing the proper number of rungs 22 supported on connected support members 24. Also, if a rod similar to that shown at 28 is unavailable, other means than the extensions 30 can be used to prevent tilting of my support fixture. I intended, therefore, to cover by the appended claims all such modifications as fall within the true spirit and scope of my invention.

What I claim as new and desire to secure by Letters Patent of the United States is:

1. A support fixture connectable in a dynamoelectric machine, having spiral brush springs, for maintaining spring lever tips in a retracted position comprising, a pair

of support members secured to a brush holder and extending outwardly therefrom, rungs secured to said members a sufficient distance from said brush holder and projecting perpendicular to the line of normal motion of the lever tips a distance sufficient to provide a platform suitable to support the spring lever tips in a retracted position allowing unrestricted access to brushes thereunder, and a cross member secured to said members for rigidly connecting them together, said support members being provided with latching means adapted to cooperate with said brush holder for preventing tilting of said support members when one or more of the tips are positioned on said rungs.

2. A support fixture, connectable in a dynamoelectric machine having spiral brush springs mounted on a transverse rod, for maintaining spring lever tips in a retracted position comprising, a pair of support members attachable to a brush holder and extending outwardly therefrom, a cross member secured to said support members for rigidly connecting them together, said support members being provided with a plurality of rigid latching means adapted to cooperate with the transverse rod for preventing tilting of the support fixture, and rungs secured to said support members and projecting perpendicular to the line of normal motion of the lever tips a distance sufficient to provide a platform suitable to support the spring lever tips in a retracted position, said rungs being positioned a sufficient distance from said first holder to allow unrestricted access to brushes thereunder with the tips retracted, said rungs being knurled on said platform to prevent slipping of the tips therefrom, said support members, cross member and rungs being maintained in position by the tension of one or more of the spring lever tips in a retracted position, and being arranged in a spaced relationship allowing unrestricted movement of the spring lever tip from a brush below one of said rungs to the retracted position above said one rung.
